UNITED STATES PATENT OFFICE

2,229,403

LAMP SOCKET

George B. Benander, Oak Lawn, R. I., assignor to
Monowatt Electric Corporation, a corporation
of Rhode Island

Application December 15, 1938, Serial No. 245,875

4 Claims. (Cl. 173—358)

This invention relates to lamp sockets, and more particularly to lamp sockets for use with lamps mounted in a decorative string, such as Christmas tree lamps. Such lamp sockets must be of small size and must be adapted for mounting on a variety of supports, such as the limbs of a Christmas tree, in a manner which permits them to be readily removed and yet held securely in place.

10 It is an object of the invention to provide a lamp socket of the type described which is of compact design employing relatively few parts which are easily assembled, which is provided with a supporting means such that it may be easily attached to a supporting object and which may be manufactured at low cost.

15 In the accompanying drawing, Fig. 1 is an elevational view of a lamp socket constructed in accordance with my invention showing the socket supported upon a limb of a Christmas tree, and provided with a decorative lamp therein; Fig. 2 is a view with part of the socket housing removed showing the interior of the socket; Fig. 3 is an exploded view of the elements of the socket; Fig. 4 is a view showing one manner of connecting the socket contacts to an electrical conductor; Fig. 5 is a view showing a modified manner of connecting the contacts to the conductor, and Fig. 6 is a perspective view of the contacts employed in the modified form of the construction shown by Fig. 5.

20 Referring to the drawing, the lamp socket 10 is provided with a housing formed in two parts 11 and 12 which are preferably formed of molded insulating material, such as a phenolic condensation product. Each half of the housing is provided with a recess 13, the wall of which is threaded so that when the parts of the housing are united together a receptacle is formed for receiving the base 14 of an electric lamp 15. Each part of the housing is identical in construction so that a description of one will suffice for a description of both.

25 At the bottom of the recess 13 is an opening 16 merging with a longitudinal groove 17 and together adapted to receive a center contact member 18. For engaging the center contact on a lamp base, the contact member 18 is provided with an extension 19 which is bent at an angle and seated within the opening 16. A second groove 20 is formed in the housing and extends from the inner wall of the recess in a direction parallel to and spaced from the groove 17. A 30 second contact member 21 is adapted to be placed

in the groove 20 and is provided with a curved extension 22 which projects inwardly from the threaded wall of the recess 13. A slot 23 extends transversely of the housing part 11 intersecting the grooves 17 and 20.

35 Each of the contact members 18 and 21 is clamped around a conducting cord 24 to provide a mechanical and electrical connection with the cord. This structure is shown most clearly by Fig. 4 which illustrates the contact 21, by way of example. Each contact is formed at one end with spaced arms 25 and 26 having pointed ends 27. The conducting cord is inserted between the spaced arms and thereafter the arms are pressed toward each other causing the contact member to grip the cord and forcing the points 27 into engagement with one of the conductors of the electric cord. The contact members 18 and 21 are placed on opposite sides of the electric cord, as shown by Fig. 3, so that each of the contacts 40 engages a separate conductor of the cord.

45 After assembly of the contact members upon the conducting cord, these elements are placed within one of the halves of the housing with the contact members 18 and 21 resting in the grooves 17 and 20, respectively, and the cord 24 seated in the slot 23. The other half of the housing is then joined with the first half to form an enclosure for the contact elements and to form a receptacle for the lamp base 14.

50 The exterior surface of the assembled housing is formed with spaced grooves 28 in the form of spiral threads which receive the convolutions of a spirally coiled wire or spring 29. The spiral wire may be threaded directly upon the assembled parts of the housing and serves to hold them securely in position. The convolutions of the wire or spring are spaced apart a distance such that the conducting cord may pass between adjacent convolutions, as shown in Figs. 1 and 2. While ordinarily the grooves 28 provide sufficient means for retaining the coiled spring around the housing, the conducting cord, by passing between the convolutions of the wire, provides additional means to prevent it from sliding off the housing under any sudden pulls.

55 Not only does the coiled spring 29 secure the two parts of the housing together, but it acts as a supporting medium for mounting the lamp socket. By extending several of the spiral convolutions beyond the socket housing a supporting means is provided which may be easily attached to a variety of objects. In the showing of Fig. 1, the spring 29 is shown attached to the limb 55

30 of a Christmas tree. Due to the fact that the convolutions of the spring may be spaced apart as occasion demands, they may be attached to objects of various sizes and shapes; at the same 5 time, the spring provides a resilient supporting means for the lamp socket and protects the attached lamp from damaging jars.

By the construction described a single element comprising the spring 29 is provided to hold 10 the parts of the socket in assembled relationship and, at the same time, provide a mounting means for the socket and lamp. Several of the socket constructions may be mounted along an electric cord simply by clamping the contact elements in the desired places and assembling the housing around them. It is unnecessary to cut 15 the cord when attaching the socket; this makes for a stronger construction since it is impossible to separate the cord and contacts and pulls on 20 the cord are transmitted directly therethrough. As shown by Fig. 2, ample contacting surface between the lamp base and the socket contacts is attained by the extension 19 which engages the center contact of the lamp base and by the curved 25 portion 22 which engages the outer contact shell of the lamp base, as the base is screwed into the recess 13.

In the form of the invention illustrated by Figs. 2, 3 and 4, the socket contacts are connected to 30 the electric cord in such a manner that the lamps are connected in parallel. In some instances it is necessary to connect the lamps in series; Figs. 5 and 6 show a construction to accomplish this result. The housing 11 is provided with 35 spaced openings 31 connected by grooves with the recess 13 for receiving the ends of the conductors 32 which are fastened therein by the contacts 33. The center contact is provided with a bent-over portion 34 for engaging the center 40 contact of a lamp base while the other contact 33 is provided with an extension 35 formed with corrugations which are aligned with the threads in the recess 13 to engage the contact shell of a lamp base. In order to make electrical connection with the conductors the contacts 33 are 45 provided with a plurality of prongs 36 which pierce the insulation of the conductor to engage the conducting wire. The contacts are secured in the openings 31 by the serrated arms 37 which 50 engage the walls of the openings and fasten the contacts in position. The contacts and conductors are assembled in the housing by placing the ends of the conductors over the openings 31 and thereafter forcing the contacts into the openings 55 so that they engage the conductors and the walls of the opening in the manner indicated. Thereafter, the other portion of the housing is placed over the assembly and the two parts of the housing are secured together by means of 60 the spring 29 in the manner shown by Figs. 1 and 2.

What I claim as new and desire to secure by Letters Patent of the United States is:

1. In a lamp socket, a two-part housing having 65 a recess therein, contact means disposed in said recess, said housing having grooves in said

parts, said grooves combining to form a helical groove over the surface of the housing when said parts are assembled with each other, and a helically coiled wire having spaced convolutions, said wire being threaded on to said groove with 5 a plurality of said convolutions seated therein surrounding the parts of said housing to secure them together and the remainder of which extend beyond said housing with the spaced convolutions being adapted to grip an object to form 10 a resilient support for said housing.

2. In a lamp socket, a two-part housing having a recess therein, said housing having a groove merging with the bottom of said recess, a second groove merging with the wall of said recess, 15 and a slot extending transversely of said grooves, contacts electrically connected to a conducting cord, said contacts resting in said grooves with the conducting cord seated in said slot, said housing having spaced guiding means on the outer 20 periphery thereof, and a helically coiled wire having spaced convolutions surrounding said housing, a portion of said convolutions cooperating with said guiding means to secure said parts together with said contacts in operative position, 25 the remainder of said convolutions extending beyond said housing and being adapted to engage a supporting member for mounting said socket.

3. In a lamp socket, a two-part housing having a recess therein, said housing having grooves merging with the bottom and side walls of said recess and a slot extending transversely of said grooves, contacts electrically and mechanically connected to a conducting cord, said contacts 30 resting in said grooves and extending into said recess for engaging the base of a lamp seated in said recess, and said conducting cord resting in said slot and extending beyond the confines of the base, said housing being provided with 40 grooves in said parts, said last-mentioned grooves combining to form a helical groove over the surface of the housing when said parts are assembled with each other, and a helically coiled wire 45 surrounding the two parts of said housing and resting in said helical groove to secure the parts together with said conducting cord extending between the convolutions of said wire, said wire having additional convolutions extending beyond said base which are adapted to grip an object 50 to form a resilient mounting means for said housing.

4. In a lamp socket, a two-part housing having a recess therein, contact means disposed in said recess, said housing having spaced guiding 55 means formed on the outer periphery thereof, and a helically coiled wire having spaced convolutions, said wire being threaded around said housing with a portion of said convolutions engaging and cooperating with said guiding means 60 to secure the parts of the housing together and the remainder of the convolutions extending beyond said housing and being adapted to grip an object to form a resilient support for said housing.

GEORGE B. BENANDER.
